UNITED STATES PATENT OFFICE.

JAMES A. MACLEOD, OF NEW HAVEN, CONNECTICUT, AND HARRY W. NOYES, OF WEST HAVEN, CONNECTICUT.

BALL-THROWING MACHINE.

1,182,024.

Specification of Letters Patent.

Patented May 9, 1916.

Application filed July 15, 1915. Serial No. 40,086.

To all whom it may concern:

Be it known that we, JAMES A. MACLEOD, residing at New Haven, in the county of New Haven and State of Connecticut, and 5 HARRY W. NOYES, residing at West Haven, in the town of Orange, in said county and State, both citizens of the United States, have invented certain new and useful Improvements in Ball-Throwing Machines, of 10 which the following is a specification, reference being had therein to the accompanying drawings.

Our invention relates to a new and improved ball throwing machine, having for 15 its object, among other things, to provide a simple and effective device for mechanically throwing a ball so that it may be delivered and travel substantially the same as a manually thrown ball.

20 To these, and other ends, our invention consists in a ball throwing machine, having certain details of construction and combinations of parts, as will be hereinafter described and more particularly pointed out 25 in the claims.

Referring to the drawings, in which like numerals of reference designate like parts in the several figures, Figure 1 is an elevation of our improved device with the connecting elements between the lever and throwing mechanism broken; Fig. 2 is a fragmentary plan view of the lever mechanism; Fig. 3 is an enlarged sectional view of the parts taken upon line A—B of Fig. 30 1; Fig. 4 is an enlarged sectional view of the parts taken upon line C—D of Fig. 1; Fig. 5 is a sectional view of the parts taken substantially upon line E—F of Fig. 6; Fig. 6 is a plan view, partly in section, of 35 the cut-off mechanism and the outer end of the throwing arm; Fig. 7 is a sectional view of the frame, tray and throwing arm, taken upon line G—H of Fig. 5; and Figs. 8 and 9 are a plan view and an elevation re- 40 spectively of a modified form of one feature of our invention.

This machine is designed for the purpose 45 of throwing a ball mechanically, with the object that a batsman may stand and practice batting, or for amusement, as desired, and it comprises mechanism for successively receiving one of a plurality of balls which are delivered to a throwing arm, and then by manipulation of a lever they are thrown 50 in a predetermined direction.

The mechanism, for purposes of description, is divided into two portions, the throwing mechanism and the lever mechanism. The latter consists of a base member 1, having a lever 2 pivotally connected therewith 60 by a pintle 3, and provided with guide bars 4, preferably arranged so that one bar is upon each side of said lever; a fixed post 5, within which a pulley 6 is pivotally mounted; a slide bar 7, having a pulley 8 rotatably 65 mounted therein; and a connecting rod 9 pivotally secured at one end to the slide bar 7 and at the other end to the lever 2 by the link 10. The throwing mechanism consists essentially of a base member 11 having two 70 substantially parallel standards 12 connected therewith, which are substantially T shape in cross section (Fig. 4).

Pivotally connected to the standards 12 near the base 11, upon the pintle 13, is the 75 throwing arm 14, which is made of spring metal of varying thicknesses, this being preferably produced by securing several tempered steel sheets together, as is common with leaf springs, and terminates at its 80 outer end in a cup 15, having a lateral containing finger 16 upon each side thereof. The end of the arm 14 opposite to the cup 15 terminates in the offset arm 26 for a purpose hereafter to be described. 85

Adjustably secured to the standards 12, by the screws 17, that pass through any one of a plurality of holes 18 in said standards, is the yoke 19, upon which is pivotally mounted a block 20, through which projects 90 the shank 21 of the tension bar 22 and held securely therein, as well as provided with means for adjustment in relation thereto, by the nuts 23. The arms 24 of the tension bar 22, upon which are mounted the rollers 25, project laterally so as to engage, in one of their positions, the side bars of the yoke 19 (Fig. 4).

The relative position of the yoke 19, upon the standards 12, is such that the tension 100 bar 22 normally hangs substantially as shown in Fig. 1. Pivotally mounted between the standards 12 upon the pintle 27 is the rock lever 28, between the arms of which is the anti-friction roller 29 upon the pintle 30. Secured to said rock lever 28 is an arm 31, to which is secured one end of the flexible connection rod 32, which passes around the pulleys 6 and 8 and is secured 105 at its other end to the eye 33 on the post 5. 110

A counter-balance weight 34 is fixed on a rod 35 that is pivotally mounted upon the pintle 27, and having a head portion 36 on its free end that lies in the path of movement of the offset arm 26.

The rock lever 28 is operated by manipulation of the lever 2 through the flexible connection 32 and as it rocks upon its pivot mounting 27 the roller 29 therein engages the offset arm 26 and moves the throwing arm 14 upon its pivot mounting 13 until it assumes substantially the position shown by broken lines in Fig. 1, at which time the cup 15 is in contact with the rollers 25 upon the tension bar 22, the arms 24 of which are in engagement with the side bars of the yoke 19. Continued pressure of the rock lever 28 causes the intermediate portion of the throwing arm 14 to yield and assume a circular position until the cup 15 thereon passes under the rollers 25, at which time the throwing arm 14, being freed from any restraint, straightens itself out by reason of its spring construction and the ball, which at that time is in the cup member 15, is by reason thereof thrown with considerable force and travels in substantially the same manner as if it had been pitched manually. Just prior to this time the offset arm 26 has engaged the head 36 of the rod 35 and lifted the counter-balance weight 34, which, when the ball is delivered and the tension removed from the throwing arm, is actuated by gravity, and the throwing arm 14 is moved upon its pivot mounting in the reverse direction until gravity exerts its influence and returns it to the position substantially shown by full lines in Fig. 1, the lever 2 being moved, of course, at substantially the same time to permit the flexible connection 32 to take up the slack caused by the movement of the lever 28.

As the throwing arm 14 moves from its throwing position to its down position, the cup 15 thereon engages the rolls 25, causing the block 20 to swing upon the yoke 19, and permits said throwing arm to pass thereby without friction or impeding its progress. It will be observed that by this method of mounting the tension bar 22, the movement of the throwing arm 14 is impeded only while moving in one direction. The relative position of the yoke 19 upon the standards 12 determines the direction and velocity of the ball as it is thrown, the holes 18 being provided to permit the desired range of both.

The balls are delivered to the cup 15 from either one or both of two chutes 37 which lead into a frame 38 fixed to the standards 12.

In the drawings I have only shown fragmentary portions of the chutes 37, these being the delivery or inner portions. The outer portions thereof may be conducted to

any convenient point and lie in a vertical or angular position in relation to the other mechanism, as may be desired, or best adapted for the position of the device. Mounted in said frame 38 so as to rock upon the pintle 39 is a tray 40 having side plates 41 and 42 adjacent to one end, which during their movement cover and uncover the recesses 43 and 44 respectively in opposite sides of the frame 38. The side plate 41 is higher than the side plate 42, this variation in height being designed so that the recess 44 may be entirely uncovered before the recess 43, whereby the chute 37 adjacent to the recess 44 will deliver its ball into the cup 15 and thereby load said cup without uncovering the recess 43, as will more particularly appear from an examination of Fig. 7 of the drawings. By this method all of the balls in one chute will be delivered to the cup member 15 before those in the other chute can enter said cup member, thereby preventing the delivery of more than one ball at a time to said cup member and the consequent clogging of the mechanism.

Upon the tray 40 is a counter-weight 45 which is adjustably secured thereto by the bolt 46, which moves through a slotted recess 47 as said counter-weight 45 is moved toward and away from the pintle 39. This counter-weight is adjusted so as to rock the tray 40 and elevate the cup 15 of the throwing arm 14, after it has been loaded, to a point where the side plate 42 will close the recess 44 and prevent another ball from entering said cup. As the throwing arm 14 moves to its down position the outer end thereof engages the tray 40 and the impact rocks the same and a ball enters the cup 15, but the tray is immediately returned to its original position by the counter-balance 45, which lifts the throwing arm 14 and the ball therein so as to prevent the lower ball of the stream of balls in either one of the chutes 37 from entering said cup.

In Figs. 8 and 9 I have shown a modified form of device for applying tension to the throwing arm 14, this being substituted for the yoke member 19 and the mechanism connected therewith. It consists essentially of the clamp plate 53 that is adjustably secured to the standards 12 by the screws 48, and upon one of which is pivotally mounted the rock arm 49 upon the pintle 50, and having the stop finger 51 thereon. In one position the outer end of the rock arm 49 engages the lug 52 fixed to one of said clamp plates and provides a barrier against which the outer end of the throwing arm engages, but when moving in the opposite direction the rock arm 49 moves upon its pivot mounting until the finger 51 engages the flange on one of the standards 12, which limits its movement in that direction and permits the

throwin' arm to pass thereby. During the next upward movement of the throwing arm 14 the cup member 15 engages the rock arm 49 and moves it back to the position shown 5 by full lines in Fig. 8, it then performing its retarding or tension function.

There are minor changes and alterations that can be made within my invention, and I would therefore have it understood that I 10 do not limit myself to the exact construction shown and described, but claim all that falls fairly within the spirit and scope of my invention.

Having described my invention, what I 15 claim as new and desire to secure by Letters Patent, is:—

1. In a ball throwing machine, the combination with a flexible throwing arm; of means for moving said throwing arm; and 20 means for retarding the movement of said throwing arm at one end so as to cause the same to bow and pass thereby, said means comprising an adjustable element having a member pivotally mounted thereon that permits movement of said throwing arm in one 25 direction and forms a barrier or obstruction thereto while moving in the opposite direction.

2. In a ball throwing machine, the combination with a flexible throwing arm; of means for moving said throwing arm; means connected with said arm for holding and carrying a ball; means for delivering balls to said holding means that permits 30 only one ball to enter at a time, and comprising a chute member, a fixed member with which said chute member is connected; a rocking cut-off member movably mounted in said fixed member; a counter-weight 35 adjustably mounted thereon; and means for actuating said cut-off member so as to permit a ball to pass from said chute into said holding and carrying means.

3. In a ball throwing machine, the combination with a flexible throwing arm; of means for moving said throwing arm; means connected with said arm for holding and carrying a ball; means for delivering balls to said holding means that permits 45 only one ball to enter at a time, and comprising a chute member, a fixed member with which said chute member is connected; a rocking cut-off member having side plates of different heights; a counter-weight 50 connected therewith; and means for actuating said cut-off member so that a ball will first move into said carrying member from the chute adjacent to the lowest of said side plates.

60 4. In a ball throwing machine, the combination with a flexible throwing arm; of means for moving said throwing arm; means connected with said arm for holding

and carrying a ball; means for delivering balls to said holding means, said means permitting only one ball to enter at a time, and comprising a fixed member to which said chute is connected; a tray pivotally mounted within said chute member, having a side plate upon each side thereof, one of said side 65 plates being higher than the other; and a counter-weight connected with said cut-off member and designed to rock said tray and return the same to a predetermined position in relation to said chute member. 75

5. In a ball throwing machine, the combination with a flexible throwing arm; of means for moving said throwing arm; means connected with said throwing arm for holding and carrying a ball; means for delivering balls to said holding means, permitting only one ball to enter at a time, and comprising a fixed member; companion chute members connected with both sides thereof; a cut-off member pivotally mounted in said 80 fixed member and in the path of movement of said throwing arm, said cut-off member having a side plate upon each side thereof adjacent to the said chute members; and a counter-weight connected with said cut-off 85 member. 90

6. In a ball throwing machine, the combination with a standard; of a flexible throwing arm pivotally connected therewith, having an offset arm at one end and 95 means for carrying a ball at the other end; a rock lever pivotally connected to said standard and having a member thereon movable in the path of said offset arm; a lever pivotally connected with said standard 100 having a head upon one end thereof in the path of movement of said offset arm; a counter-balance weight upon the other end of said lever; and means for actuating said rock lever. 105

7. In a ball throwing machine, the combination with a standard; of a flexible throwing arm pivotally connected therewith, having an offset arm at one end and means for carrying a ball at the other end; 110 a rock lever pivotally connected to said standard and having a member thereon movable in the path of said offset arm; a lever pivotally connected with said standard having a head upon one end thereof in the path of movement of said offset arm; a counter-balance weight upon the other end of said lever; means for actuating said rock lever; a manually actuated lever; and a connection between said manually actuated lever and rock lever. 115 120

In testimony whereof we have hereunto affixed our signatures.

JAMES A. MACLEOD.
HARRY W. NOYES.
